UNITED STATES PATENT OFFICE.

MILLARD F. COX, OF LOUISVILLE, KENTUCKY.

SELF-ADJUSTING STAY-BOLT.

1,072,315.

Specification of Letters Patent.

Patented Sept. 2, 1913.

Application filed October 30, 1912. Serial No. 728,706.

To all whom it may concern:

Be it known that I, MILLARD F. Cox, a citizen of the United States, residing at Louisville, in the county of Jefferson and 5 State of Kentucky, have invented certain new and useful Improvements in Self-Adjusting Stay-Bolts, of which the following is a specification.

This invention relates to an improvement 10 in stay bolts and particularly to self-adjusting stay bolts for staying two walls between which relative movement or vibration is liable to occur when in use, as for instance the walls of steam boilers, the improved device being intended to displace the rigid stay bolt wherever used, as for instance when staying the roof, sides and back and front sheets of fire boxes or similar structures.

20 The object of the invention is to properly brace the walls and avoid the breaking incident to rigid stay bolts, as well as to compensate for error in design and irregularities of construction, with particular reference to the movements of boiler sheets under expansion and contraction, the effects of which in all types of locomotive boilers are so difficult to definitely trace.

25 The invention will be fully understood 30 upon reference to the illustrative embodiments thereof disclosed in the accompanying drawing, in which—

Figures 1, 2, 3 and 4 are axial sections 35 showing fragmentary portions of two boiler sheets stayed, in each instance, by the self-adjusting stay bolt forming the subject matter of the present invention; each view showing the same bolt head seat and cap associated with a different size of bolt; Figs. 40 5 and 5^a show, by top plan view and axial section, a form of cap suitable for use in carrying out the present invention, and Figs. 6 and 6^a show, by side elevation and axial section, the bolt head and the threaded 45 sleeve forming the seat therefor.

1, 2, represent the outer boiler sheet and the fire box wall of a locomotive steam boiler.

3 is the stay bolt which is threaded and 50 riveted at 4 in the inner wall 2 and is connected to the outer wall by a seat 5 which permits the bolt to adjust itself angularly in response to relative movement in the planes of the sheets, and also to permit vibration of the bolt without imposing 55

strains upon it; this seat being provided with a cap 6 which renders it steam tight.

The novel construction of the bolt with its seat and cap constitutes the subject matter of the present invention, as will now be 60 described.

The seat member 5 comprises a sleeve screwed into the outside sheet 1 of the fire box by an external thread 5^a, preferably tapered to insure a steam-tight fit; said 65 sleeve having an enlarged upper end 5^d formed with a concaved recess 5^e to receive the head 3^a of the bolt, and this enlargement being formed with a thread 5^b preferably straight and on the outside, to receive the 70 threaded cap 6. The cap thread is not required to be absolutely steam-tight, since the cap is constructed with a sealing shoulder 6^a pressing tightly and grinding upon the 75 upper edge of the sleeve 5, as the cap is screwed home, which makes a tight joint at that point. Moreover, the bolt head is fitted to its seat with sufficient accuracy to prevent escape of steam when the boiler is under pressure and the bolt subject to tension. 80

The head of the bolt and the concave seat formed in the sleeve provide a ball-and-socket joint, which allows limited angular movement to the bolt in any direction without diminishing the bearing of the head in 85 the seat, so that the bolt can accommodate or adjust itself automatically in harmony with any movement or vibration which may develop in the fire box in consequence of changes in temperature or shocks transmitted from the track. 90

The enlargement of the upper end of the sleeve permits the concave bearing to be made larger and to be located immediately over the straight wall 5^e of the sleeve, without making the wall of the sleeve unduly thick or tapering it. Moreover, it accommodates a laterally enlarged head with corresponding increase in the radius R of the surface with which the head bears upon the 100 seat, thereby greatly increasing the angle of this bearing surface to the axis of the bolt and correspondingly reducing the wedging effect and consequent tendency to split the sleeve when excessive loads are imposed upon the stay bolt. A further advantage of the lateral enlargement of the sleeve and the location of the concave seat vertically above the relatively thin cylindrical body of the sleeve, accrues from the 110

increased clearance between the neck of the bolt and the inner surface of the sleeve extending from the head to the lower end of the sleeve, and the avoidance of taper or reduction in the upper end of this space with consequent liability to retain and accumulate scale and sediment, which in some forms of stay bolt construction, eventually pack around the bolt sufficiently to prevent its yielding.

The upper portion of the head of the bolt is constructed on two different curves, to wit, a side curve, the radius r of which is less than half the greatest cross dimension 15 of the head, and a top curve, the radius r' of which is approximately equal to said dimension, with the result that surplus metal and unnecessary weight are wholly eliminated without removing metal necessary to 20 afford shearing resistance. This construction permits the use of a relatively low cap without sacrificing any of the advantages of the cap space.

The general shape of the bolt head resulting from the characteristics of construction 25 above described is elliptical in axial section which, while affording the necessary wide ball bearing seat with increased angle of bearing surface, permits the embodiment of 30 a minimum weight of material with a maximum strength and durability. It also adapts the bolt to be made by pressing or upsetting with ease; and hence tends to cheapness in construction as well as in material. These 35 same considerations also enter into the construction of the sleeve providing the seat and the cap appropriate to the particular construction of sleeve and bolt head.

In forming the head, its lower bearing 40 surfaces will be constructed upon an arc struck from a center which is considerably beyond the greatest cross dimension of the head and preferably with a radius that is greater than half the diameter of the head 45 so as to give the increased angle to the radius to reduce the tendency to split the

sleeve by wedging action. The sides of the head above the bearing surfaces will be constructed upon two radii considerably less than the diameter of the head, while the outer surface will be constructed relatively flat by selecting an arc whose center is well beyond the greatest cross dimension of the head. The head is joined to the neck of the bolt by fillets to avoid a sharp angle and the center of the outer surface of the head may be provided with a faced recess to receive a tool for screwing the bolt into the inner sheet.

A further advantage arising from this 60 construction is that bolts of different diameters can be used with the same seating attachment, so that when a broken bolt is removed from the inner sheet, necessitating reaming and rethreading of the opening, a 65 larger bolt fitting the new opening can be introduced into the same seating attachment.

I claim:—

A self-adjusting stay bolt for uniting two members, comprising a body portion 70 adapted to connect with one member, and a head adapted to coöperate to effect a ball and socket bearing upon the other member, said head being formed with an inner spherical bearing face constructed upon an 75 arc whose radius is greater than half the greatest cross dimension of the head, whereby the wedging action of the head is reduced; said head also having its crown constructed on two different curves, to wit, a 80 side curve, the radius of which is less than half said dimension and a top curve, the radius of which is approximately equal to said dimension.

The foregoing specification signed at 85 Louisville, Ky., this 16th day of October, 1912.

MILLARD F. COX.

In presence of—

E. B. VAUGHAN,
H. R. CRULL.
